UNITED STATES PATENT OFFICE.

FREDERIC H. BENDER, OF CHICAGO, ILLINOIS, ASSIGNOR TO AMERICAN STEEL FOUNDRIES, OF CHICAGO, ILLINOIS, A CORPORATION OF NEW JERSEY.

DRAFT-RIGGING-SUPPORTING ARRANGEMENT.

Application filed August 4, 1924. Serial No. 729,921.

This invention relates to draft rigging supporting means and more particularly to retaining means for self-centering devices.

The use of a self-centering device broadly is old. Heretofore such devices have been mounted on carry irons in a manner tending to prevent displacement of the self-centering device with respect to the carry iron. For the most part such arrangements are generally successful, except when a car is turned over, whereupon the self-centering device has been free to drop away from the carry iron and be lost.

One object of the invention is to provide simple, reliable and durable means for retaining a self-centering device in its proper association with the carry iron under both normal and abnormal circumstances.

Another object is to provide an arrangement in which selective retaining means may be used for preventing displacement of a self-centering device.

Another object is to provide a simple and efficient combination of carry iron, self-centering device and retaining means adapted to meet all of the requirements under conditions which are encountered in service.

These and other objects are accomplished by means of the arrangement disclosed by the accompanying sheet of drawings in which—

Figure 1 is a front elevation of a striking block or casting having a carry iron integrally formed therewith, a self-centering device and retaining means for said self-centering device to prevent displacement of the latter.

Figure 2 is a sectional view taken in the plane of line 2—2 of Figures 1 and 3, and showing a vertical bolt for retaining the self-centering device against displacement.

Figure 3 is a sectional view taken in the plane of lines 3—3 of Figure 2.

Figure 4 is a detailed sectional view taken in the plane of line 4—4 of Figure 3 and showing the elongated ears or projections forming the head of the vertical retaining bolt.

Figure 5 is a sectional view taken in the plane of line 5—5 of Figure 6 and somewhat similar to that shown in Figure 2 but showing a horizontally arranged retaining bolt instead of a vertically arranged retaining bolt, and

Figure 6 is a sectional view taken in the plane of line 6—6 of Figure 5.

The various novel features of the invention will be apparent from the following description and drawing and will be particularly pointed out in the appended claims.

Referring to the figures of the drawings, it will be noted that the invention is illustrated in connection with a striking casting 10 having integrally formed therewith a carry iron 11. A self-centering device including a carriage 12 is mounted upon rollers 13, supported by the carry iron 11 whereby the carriage 12 may have a transverse movement with respect to the carry iron 11 occasioned, for example, when the car to which the mechanism is attached is rounding a curve or encountering track irregularities. The carriage 12 automatically is made self-centering by virtue of the fact that the rollers 13 are mounted between concave surfaces 14 and 15 respectively of the carry iron 11 and carriage 12.

Under normal operating conditions the carriage 12 or self-centering device is prevented from moving into an inoperative position with respect to the carry iron 11, due to the fact that the carriage 12 is mounted down in between the transverse side walls 16 of the carry iron 11. However, entire reliance should not be placed upon the overlapping of the carriage 12 and side walls 16 of the carry iron 11 under all circumstances to prevent displacement of the carriage 12 with respect to the carry iron, for it is apparent that under some circumstances, for example, when a railroad car is tipped over, it would be possible for the carriage or self-centering device 12 to be entirely disengaged from the carry iron 11 and lost.

This will be particularly true when it is realized that the degree of overlap between the carriage 12 and the side walls 16 is not as great as the clearance between the top interior wall 17 of the striking casting 10 and the top wall 18 of the coupler shank 19, which is mounted upon and supported by the carriage 12. This condition necessarily must exist to facilitate the assembly of the coupler and self-centering device within the striking casting 10, particularly where the carry iron 11 is formed integrally with the striking casting.

To retain the self-centering device within

the striking casting under both normal and abnormal conditions, I have provided a selective retaining arrangement. In this connection, it will be noted that the self-centering device or carriage 12 is provided with a longitudinally extending opening 20 throughout its length and through which a longitudinal bolt 21 may pass, as shown particularly in Figures 5 and 6 and in dot and dash lines in Figure 1. This horizontally arranged retaining bolt not only cooperates with the self-centering device 12 but also with the side walls 22 of the striking casting, it being noted that the longitudinally arranged retaining bolt 21 passes through openings 23 in the side walls 22. Normally the horizontally arranged retaining bolt 21 is out of supporting relationship with respect to the self-centering device, that is to say, the horizontally extending retaining bolt 21 does not engage any part of the self-centering device and on the other hand extends through the opening 20 therein and has a relatively large clearance with respect thereto to permit a free horizontal swinging movement of the self-centering device 12 and the attendant vertical movement occasioned by the riding of said self-centering device on the rollers 13.

The self-centering device may be retained against displacement by the use of a vertical retaining bolt as distinguished from the horizontal retaining bolt. To accomplish this result a vertical retaining bolt 24 is passed through vertical alignment openings 25 and 26 in the carry iron 11 and carriage 12. The opening 25 in the carry iron is elongated and defined by the side walls 27 to permit free horizontal movement of the carriage or self-centering device 12. The opening 26 in the carriage 12 is elongated transversely with respect to the elongation of opening 25 to permit an upwardly vertical insertion of the vertical retaining bolt 24 and more particularly to permit free vertical movement of the projections 28 forming the head of the vertical retaining bolt. After the vertical retaining bolt 24 is thus raised through the openings 25 and 26 until the head is lifted above the horizontal sur-

face 29 within opening 20, the bolt 24 may be rotated through an angle of 90 degrees on its vertical axis to permit the head projection 28 to drop down into pockets 30 formed in the carriage 12 to prevent accidental upward movement of the bolt 24. Upward movement of the bolt 24 normally is prevented by a key 31 which is passed through the bolt after the latter is set in position.

By means of this arrangement the carriage or self-centering device is selectively retained against displacement under both normal and abnormal conditions.

It is my intention to cover all modifications of this invention falling within the spirit and scope of the following claims.

I claim:

1. In draft rigging supporting means, a striking block having a carry iron, a self-centering device supported thereby having different portions extending in different directions engageable by retaining means, means extending in one direction engageable with one of said portions for retaining said self-centering device against displacement, another portion of said device being engageable with other retaining means extending in a different direction.

2. In draft rigging supporting means, a striking block having a carry iron, a self-centering device having a plurality of openings extending in different directions, and means passing through one of said openings for retaining said self-centering device against displacement, the other opening being adapted to receive a different retaining means.

3. In draft rigging supporting means, a striking block having a carry iron, a self-centering device supported thereby and having a horizontally extending opening and a vertically extending opening, said openings being selectively used for the reception of a retaining member to prevent displacement of said self-centering device.

Signed at Chicago, Illinois, this 31st day of July, 1924.

FREDERIC H. BENDER.
